(57) **CLAIM**

The ornamental design for a hand of a watch dial, as shown and described.

DESCRIPTION

FIG. 1 is a front view of a hand of a watch dial showing the new design with the hand in the 12:00 position;

FIG. 2 is a front view thereof showing the hand in the 2:00 position;

FIG. 3 is a front view thereof showing the hand in the 4:00 position;

FIG. 4 is a front view thereof showing the hand in the 6:00 position;

FIG. 5 is a front view thereof showing the hand in the 8:00 position; and

FIG. 6 is a front view thereof showing the hand in the 10:00 position; and,

FIG. 7 is a front, right, and bottom perspective view showing the hand in the 12:00 position.

The broken line showing of the watch case is for the purpose of illustrating portions of the article and forms no part of the claimed design.
